SELECTIVE SOLVENT REFINING PROCESS AND SOLVENT RECOVERY

Frederic C. McCoy, Beacon, N.Y., and Marshall R. McClure, Jr., Port Arthur, Robert A. Woodle, Nederland, and Robert L. Murphey, Groves, Tex., assignors to Texaco Inc., a corporation of Delaware

Application April 16, 1958, Serial No. 728,806

9 Claims. (Cl. 208—321)

This invention relates to the recovery of selective solvent from admixture with hydrocarbons and to a petroleum treating process involving a solvent refining operation. In accordance with one embodiment this invention relates to an improved petroleum solvent refining operation. In accordance with another embodiment this invention is directed to an improved method of recovering selective solvent from admixture with hydrocarbons, particularly hydrocarbons having a similar boiling point.

In a solvent refining operation as usually practiced in the petroleum refining industry a liquid selective solvent evidencing a preferential solubility for one portion of a petroleum fraction over another portion of a petroleum fraction is employed to effect separation of the petroleum fraction into various components. Usually a selective solvent which is a selective solvent for aromatic hydrocarbons over less aromatic or non-aromatic hydrocarbons is employed. Subsequently in the petroleum refining operation the selective solvent is separated from the resulting raffinate and extract by distillation. In some instances, however, the boiling point of a portion of the petroleum fraction undergoing fractionation by solvent extraction closely approximates the boiling point of the particular selective solvent employed. In these instances the separation of the selective solvent from the raffinate and/or extract by fractional distillation is difficult or uneconomical. More particularly, it has been proposed to effect a fractionation of petroleum naphtha fraction and the like into aromatic and relatively less aromatic portions by solvent extraction employing liquid furfural as the selective solvent. Unfortunately, however, the boiling point of furfural (about 324° F.) is within the range of the boiling points of the constituents separated with the result that substantially complete separation of the furfural from the resulting raffinate and extract by fractional distillation is difficult.

Accordingly, it is an object of this invention to provide an improved method for the solvent refining of petroleum fractions containing components having a boiling point approaching that of the selective solvent employed.

Another object of this invention is to provide an improved method for the recovery or separation of a selective solvent from substantially co-boiling hydrocarbons.

Another object of this invention is to provide an improved method for the recovery of furfural from a raffinate mix or from an extract mix produced in a furfural solvent refining operation of a petroleum fraction, such as a heavy naphtha or a fraction in the kerosene boiling range, particularly a petroleum fraction having an initial boiling point (I.B.P.) below about 625° F.

Still another object of this invention is to provide an improved method, involving washing or a subsequent solvent extraction operation, for the recovery of a normally liquid polar organic selective solvent from admixture with hydrocarbons.

How these and other objects of this invention are accomplished will become apparent in the light of the accompanying disclosure made with reference to the accompanying drawings wherein:

Fig. 1 schematically illustrates a solvent refining process in accordance with the practice of this invention, and wherein

2

Fig. 2 schematically illustrates one embodiment of the practice of this invention in a solvent refining operation directed to the recovery of selective solvent, and wherein

Fig. 3 schematically illustrates another embodiment of the practice of this invention directed to the recovery of a selective solvent, and wherein

Fig. 4 schematically illustrates another embodiment of the practice of this invention directed to the recovery of selective solvent employed in a solvent refining operation.

10 In accordance with our invention we have discovered that a normally liquid selective solvent, such as a normally liquid polar organic selective solvent for aromatic hydrocarbons, is advantageously separated from single liquid phase admixture with hydrocarbons by contacting said admixture with an aqueous hydrotropic solution which exhibits a preferential solubility for said selective solvent and which it at least partially immiscible with the admixture undergoing treatment. There is recovered from the aforesaid contacting operation a resulting aqueous hydrotropic solution now containing selective solvent dissolved therein.

The aqueous hydrotropic solution employed in the practice of this invention comprises an aqueous solution of a hydrotropic, that is, a material such as a water soluble salt, e.g., salt of an organic acid, which when dissolved in water increases the solvent power of water for polar organic materials normally insoluble or only sparingly soluble in water. Any hydrotropic which when dissolved in water yields an aqueous hydrotropic solution having an increased or preferential solubility for normal liquid polar organic compounds, is suitable for use in the practice of this invention. Typical suitable hydrotropes include the water soluble alkali metal arylsulfonates, particularly the water soluble, relatively low molecular weight sodium arylsulfonates and sodium alkarylsulfonates such as sodium benzenesulfonate, potassium benzenesulfonate, sodium toluenesulfonate, potassium toluenesulfonate, and the sodium xylenesulfonates and the potassium xylenesulfonates. Generally an arylsulfonate, 40 which includes alkarylsulfonates, e.g., C_1-C_{10} alkyl-substituted benzenesulfonates, containing less than 16 carbon atoms per molecule is suitable. Other suitable hydrotropes include the water soluble salts of aliphatic monocarboxylic acids and the alkali metal alkylsulfonates derived from the corresponding alkanes, such as propane, butane, pentane, hexane, heptane and the like.

Other known hydrotropes or hydrotropic agents, and mixtures thereof, are suitably employed in the practice of this invention. It is preferred in the practice of this invention to employ concentrated aqueous hydrotropic solutions, such as aqueous solutions wherein the concentration of the hydrotropic is in the range 10-70% by weight, more or less, usually in the range 20-60% by weight.

55 Referring now to Fig. 1 of the drawing which schematically illustrates one embodiment of the practice of this invention as applied to the solvent refining of a charge oil, such as a heavy petroleum naphtha or kerosene fraction or light lubricating oil, for the removal of aromatic hydrocarbons therefrom, a charge oil is introduced via line 11 into liquid-liquid solvent-refining zone 12 wherein it is brought into direct countercurrent contact with a liquid selective solvent, furfural, preferably water-saturated furfural, which is introduced into the upper portion of solvent refining zone 12 via line 14. Additional fresh furfural, as required, is added to solvent refining zone 12 from a convenient source, not shown, via line 15 to line 14. Within solvent refining zone 12 the charge oil is brought into intimate contact with the liquid selective solvent, water-saturated furfural. The solvent refining zone 12 may be operated under isothermal conditions or at a temperature gradient, one end

of the refining zone having a temperature different from the other end of the solvent refining zone. The ratio of selective solvent to charge oil introduced into solvent refining zone 12 will vary depending upon the characteristics of the charge stock and the extent of refining desired. Usually a solvent to charge oil volume ratio in the range .5 to 10.0 is employed.

There is recovered from the upper portion of solvent refining zone 12 via line 16 a liquid raffinate mix. The raffinate mix comprises the less aromatic hydrocarbons containing furfural dissolved therein. There is recovered from the other end of solvent refining zone 12 via line 18 a liquid extract mix. The extract mix comprises liquid selective solvent, furfural, containing the more aromatic hydrocarbons selectively extracted from the charge oil dissolved therein. The raffinate mix is introduced via line 16 into the lower end of raffinate mix stripper 19 wherein it is subjected to direct countercurrent liquid-liquid contact with a concentrated aqueous hydrotropic solution, such as a 40% by weight solution of sodium xylenesulfonate, which is introduced into the upper end of raffinate mix stripper 19 via line 20. Similarly, the extract mix from solvent refining zone 12 is introduced via line 18 into the lower end of extract mix stripper 21 wherein it is subjected to direct, liquid-liquid countercurrent contact with the aforesaid aqueous hydrotropic solution which is introduced into the upper end of extract mix stripper 21 via line 22. There is recovered from the upper end of extract mix stripper 21 via line 24 a liquid extract comprising substantially only the aromatic hydrocarbons derived from the charge oil, said extract being substantially free of furfural. There is also recovered from the upper end of raffinate mix stripper 19 via line 25 a liquid raffinate comprising the more paraffinic hydrocarbons originally present in said charge oil, said raffinate being substantially free of the selective solvent, furfural.

There is recovered from the lower end of raffinate mix stripper 19 via line 26 the aqueous hydrotropic solution now containing furfural dissolved therein. Similarly, there is recovered from the lower end of extract mix stripper 21 via line 28 another stream of aqueous hydrotropic solution containing the selective solvent, furfural, dissolved therein.

Extract mix stripper 21 and raffinate mix stripper 19 are operated at a suitable temperature, such as a temperature in the range 70-220° F., more or less, depending upon the temperature conditions desired therein. The furfural-rich aqueous hydrotropic solution recovered from strippers 19 and 21 via lines 26 and 28, respectively, are admixed in line 28 and introduced into hydrotropic concentrator 29 wherein the furfural is distilled overhead as a furfural-water azeotrope or constant boiling mixture (C.B.M.) via line 30. The furfural-water azeotrope is condensed by condenser 31 and the resulting condensate introduced via line 32 into decanter or separator 34 wherein it separates into a lower furfural or furfural-rich phase and a supernatant water or water-rich phase. The furfural-rich phase comprises furfural saturated with water and the supernatant water-rich phase comprises water saturated with furfural.

The furfural-rich phase is recovered from decanter 34 via line 14 for reintroduction into solvent refining zone 12 to effect solvent refining of additional charge oil. The furfural-saturated water phase is removed from decanter 34 and introduced via line 35 as reflux into the upper portion of hydrotropic concentrator 29. Desirably hydrotropic concentrator 29 is operated under conditions such that substantially no steam injection is required. This is accomplished by withdrawing a bottoms fraction containing the substantially furfural-free concentrated hydrotropic solution via line 36 and introducing the same into reboiler 38 which is supplied with a suitable heating fluid such as steam to the heater or heat exchanger 39 therein.

The vapor generated within reboiler 38 is introduced via line 40 into the lower portion of hydrotropic concentrator 29. The resulting hot concentrated, furfural-free aqueous hydrotropic solution is recovered from reboiler 38 via line 41 and introduced, after suitable cooling, if desired, by means not shown, via lines 20 and 22 into strippers 19 and 21, respectively, for the recovery of furfural from the raffinate mix and extract mix issuing from the solvent refining zone. Make-up water, if desired or if required, may be introduced into the system from a suitable source, not shown, via lines 42 and 36 into reboiler 38.

In accordance with another embodiment of the practice of this invention the relatively furfural-lean aqueous hydrotropic solution issuing from the lower end of raffinate mix stripper 19 via line 26 may be employed, in whole or in part, to extract additional furfural from the extract mix in extract mix stripper 21 by introduction thereto via lines 26, 44 and 22.

Accordingly, in the manner described hereinabove with respect to Fig. 1, the practice of our invention is applied to the recovery of furfural from an extract mix and a raffinate mix derived from a furfural solvent refining operation wherein an aqueous hydrotropic solution is employed to separate furfural from hydrocarbons present in said mixes.

Referring now to Fig. 2 of the drawing there is schematically illustrated another embodiment of the practice of this invention directed to the recovery of furfural from an extract mix issuing from a furfural solvent refining zone, such as solvent refining zone 12 of Fig. 1, and the recovery of the furfural from the resulting furfural-rich aqueous hydrotropic solution. Although the particular embodiment of the practice of this invention is illustrated in Fig. 2 with respect to the recovery of selective solvent, furfural, from extract mix, this embodiment of applicants' invention is also applicable to the recovery of selective solvent from a raffinate mix issuing from a solvent refining zone, such as solvent refining zone 12 of Fig. 1.

As illustrated in Fig. 2 extract mix, such as furfural extract mix derived from solvent refining zone 12 via line 18 of Fig. 1, is introduced via line 51 into extract mix stripper 52 wherein it is brought into direct liquid-liquid countercurrent contact with an aqueous hydrotropic solution, such as a concentrated aqueous solution of sodium xylene sulfonate. The aqueous hydrotropic solution is introduced into the upper end of extract mix stripper 52 via line 54. There is recovered from one end of extract mix stripper 52 via line 55 extract now substantially free of furfural and comprising substantially only more aromatic hydrocarbons. There is recovered from the other end of extract stripper 52 via line 56 a furfural-rich aqueous hydrotropic solution which is introduced via this same line into hydrotropic concentrator 58. Hydrotropic concentrator 58 is supplied with a suitable heating element 59 through which flows a suitable regulated heating fluid, such as steam. The amount of steam flowing through heating element 59 is regulated by flow controller 60 in accordance with the temperature and/or flow of vapors issuing from concentrator 58 via line 61.

The vapors from concentrator 58 via line 61 are introduced into condenser 62 wherein they are condensed and from which the resulting condensate flows via line 64 into decanter 65 wherein the condensate separates into a water-saturated furfural phase which is recovered via line 66 and a furfural-saturated water phase which is recovered via line 68. The furfural-saturated water phase is reintroduced into concentrator 58 via lines 68 and 56. The hydrotropic concentration of the aqueous solution within concentrator 58 as well as the liquid level of the solution therein is regulated and controlled by the use of water introduced into concentrator 58 via lines 67 and 56. The flow of this make-up water into concentrator 58 is controlled by liquid level controller 69.

Within concentrator 58 the furfural-rich aqueous hydrotropic solution introduced thereto via line 56 is concentrated by the removal of furfural and water therefrom as a constant boiling mixture in the vapors issuing overhead via line 61. There is recovered from concentrator 58 via line 70 a concentrated hydrotropic solution, now relatively lean with respect to or substantially free of furfural. The flow of substantially furfural-free concentrated hydrotropic solution from concentrator 58 via line 70 is regulated by flow control valve 71 operatively connected to concentration controller 72 which in turn is operatively connected to concentrator 58.

The resulting substantially furfural-free or partially stripped aqueous hydrotropic solution issuing from concentrator 58 via line 70 is introduced into the upper portion of hydrotropic solution stripper 74 wherein it is subjected to direct liquid-liquid countercurrent contact with a suitable liquid hydrocarbon, such as charge oil from which the extract mix in line 51 may be suitably derived, as illustrated in Fig. 1. The charge oil or other suitable hydrocarbon or petroleum fraction is introduced into hydrotropic solution stripper 74 via line 75 to strip any residual furfural present in the aqueous hydrotropic solution introduced into stripper 74 via line 70. Accordingly there issues from the upper portion of stripper 74 via line 76 a charge oil now containing furfural dissolved therein. Desirably this charge oil containing furfural is applied as feed to a suitable solvent refining operation, as illustrated in Fig. 1 of the drawings. Also, there is recovered from the lower end of stripper 74 via line 54 an aqueous hydrotropic solution now substantially free of furfural. This furfural stripped aqueous hydrotropic solution issuing from stripper 74 via line 54 is employed for the extraction of furfural from the extract mix within extract mix stripper 52.

Referring now to Fig. 3 of the drawing, which schematically illustrates another embodiment of the practice of this invention and wherein the same reference numerals have been employed to designate similar apparatus and elements as found in Fig. 2 of the drawings, extract mix is introduced via line 51 into extract mix stripper 52 wherein it is brought into direct liquid-liquid countercurrent contact with a partially stripped aqueous hydrotropic solution introduced into the upper portion of stripper 52 via line 54. There is recovered from the upper portion of stripper 52 a partially stripped extract mix via line 55. Also there is recovered from the lower end of stripper 52 via line 56 a furfural-rich aqueous hydrotropic solution which is introduced into hydrotropic concentrator 58 wherein it is concentrated by the application of heat thereto by means of heating element 59 which is operatively connected with the temperature and/or flow or vapors emanating from concentrator 58 via line 61. These vapors in line 61 are condensed in condenser 62 and the resulting condensate introduced via line 64 into decanter 65 wherein they separate into a water-saturated furfural phase which is removed via line 66 and a furfural-saturated water phase which is removed via line 68 for reintroduction into concentrator 58 via line 56. Make-up water is introduced into concentrator 58 via lines 67 and 56. The amount of make-up water introduced into concentrator 58 is controlled by a flow control valve operatively connected with concentrator liquid level controller 69. Similarly the flow of the resulting concentrated aqueous hydrotropic solution issuing from concentrator 58 via line 54 is regulated by flow control valve 71 operatively connected to concentration controller 72.

The partially furfural stripped extract mix issuing overhead from stripper 52 via line 55 is introduced into final extract mix stripper 81 wherein it is subjected to direct liquid-liquid countercurrent contact with water introduced into the upper portion of stripper 81 via line 82. There issues from the upper portion of stripper 81 a substantial-

ly furfural-free extract via line 84. There is recovered from the lower end of stripper 81 via line 85 furfural-rich water which is introduced into the upper end of water stripper 86 wherein it is subjected to direct liquid-liquid countercurrent contact with a liquid petroleum fraction, such as a charge oil from which the extract mix was derived, introduced into the lower end of water stripper 86 via line 88. There is recovered from the upper end of water stripper 86 via line 89 charge oil now containing furfural dissolved therein, the furfural dissolved in the charge oil recovered from stripper 86 via line 89 being the furfural originally present in the partially stripped extract mix introduced via line 55 into extract mix stripper 81. Also there is recovered from the lower end of water stripper 86 via line 82 water now substantially free of furfural. This water is then introduced via line 82 into the upper end of extract mix stripper 81 to effect removal of furfural from the partially stripped extract mix therein.

Referring now to Fig. 4 of the drawing which schematically illustrates another embodiment of the practice of this invention as applied to the recovery of furfural from an aqueous hydrotropic solution employed for the recovery of a selective solvent, extract mix containing furfural dissolved therein is introduced via line 90 into extract mix stripper 91. Within stripper 91 the extract mix is subjected to direct liquid-liquid countercurrent contact with an aqueous hydrotropic solution for the recovery of the selective solvent therefrom. The aqueous hydrotropic solution is introduced into the upper end of stripper 91 via line 92. There is recovered from the upper end of stripper 91 via line 94 a substantially furfural-free extract. There is also recovered from the lower end of stripper 91 via line 95 a relatively furfural-rich aqueous hydrotropic solution which is then introduced into the upper end of hydrotropic stripper 96. Within hydrotropic stripper 96 the furfural-rich aqueous hydrotropic solution is subjected to direct liquid-liquid countercurrent contact with a relatively low boiling or readily separable, as by fractional distillation, hydrocarbon or hydrocarbon fraction introduced into the lower end of hydrotropic stripper 96 via line 97.

As a result of the above-indicated operations there is recovered from the lower end of hydrotropic stripper 96 via line 92 an aqueous hydrotropic solution substantially free of furfural. There is recovered overhead from hydrotropic stripper 96 via line 98 furfural dissolved in the relatively low boiling or readily separable hydrocarbon. The low boiling hydrocarbon containing furfural is introduced via line 98 into fractionator 99 wherein the relatively low boiling hydrocarbon is removed overhead via line 100, condensed in condenser 101 and the resulting condensate supplied via line 102 into flow splitter 104 wherein a portion of the resulting condensed hydrocarbon is returned via line 105 as reflux to fractionator 99. Another portion of the condensed low boiling hydrocarbon is returned via lines 106 and 97 to hydrotropic stripper 96. The bottoms issuing from the lower end of fractionator 99 via line 108 are introduced into reboiler 109 which is supplied with heating element 110 supplied with suitable heating fluid. The vapors generated within reboiler 109 are returned to fractionator 99 via line 111 and the remaining bottoms fraction comprising furfural substantially free of the low boiling hydrocarbon is removed via line 112. In this embodiment of the practice of applicants' invention a low boiling hydrocarbon, such as a hydrocarbon or hydrocarbon fraction readily separable by distillation from the selective solvent associated therewith, is employed in lieu of distillation to effect removal of furfural from the furfural-rich aqueous hydrotropic solution. Desirably the low boiling hydrocarbon or hydrocarbon fraction employed is an aromatic hydrocarbon, such as benzene, or a hydrocarbon fraction which is readily miscible with the selective solvent (furfural) employed.

The following is exemplary of the practice of this invention. Various petroleum refinery stocks, the properties of which are set forth in accompanying Table I, were subjected to furfural solvent refining under varying conditions. The resulting extract mixes and raffinate mixes derived from the solvent refining operations were then subjected to direct countercurrent liquid-liquid contact with a concentrated aqueous hydrotropic solution, viz. a 40% by weight aqueous solution of sodium xylene-sulfonate to remove residual selective solvent, furfural, from the raffinate mix and the extract mix. Following the foregoing operations there were recovered substantially furfural-free raffinates and extracts. The test data observed during the foregoing solvent refining operations together with the properties of the resulting recovered raffinates and extracts are set forth in accompanying Tables II, III and IV.

Extract mixes derived from the foregoing indicated furfural solvent refining operations were countercurrently contacted with a 40% by weight aqueous solution of sodium xylenesulfonate, at a temperature of about 150° F. and employing a varying hydrotropic solution dosage in the range 100-300% by volume. The furfural extract mixes employed contained a major amount by volume, about 80%, furfural. There was recovered from these operations an extract having a furfural content of less than about 0.03% by weight, even less than 0.01% by weight. It was observed that by employing a hydrotropic solution to extract mix dosage greater than 215% volume, basis extract mix, a washed extract having less than 0.03% by weight furfural was obtained.

The resulting fat, furfural-rich aqueous hydrotropic solutions were separated into furfural and aqueous hydrotropic solution by fractional distillation. For example, a furfural-rich aqueous hydrotropic solution comprising 19-20% furfural after having been subjected to fractional distillation yielded an aqueous hydrotropic solution containing in the range 32.8-36.3% by weight solids and a substantially insignificant amount of furfural, in the range 0.1-0.8% by weight.

Likewise, with respect to the solvent extraction of raffinate mixes wherein the selective solvent, furfural, comprises only a minor portion thereof it was observed that substantially the same dosage, about 225% by volume basis raffinate mix, was required in order to reduce the furfural content of the raffinate to a substantially insignificant value, about 0.03% by weight. In these tests which were also carried out at a temperature of about 150° F. on a laboratory eight stage box counterflow unit employing 40% by weight aqueous solution of sodium xylenesulfonate as the aqueous hydrotropic solution the raffinate mix undergoing treatment contained approximately 15% furfural.

During the foregoing tests it was observed that the recovered aqueous hydrotropic solution was more effective than freshly prepared hydrotropic solution in removing furfural from admixture with the accompanying hydrocarbons. The data setting forth the superiority of recovered or used aqueous hydrotropic solutions over fresh aqueous hydrotropic solutions for the recovery of selective solvent, furfural, is set forth in accompanying Table V.

TABLE V

As indicated hereinabove, the practice of this invention is useful for the separation of a normally liquid polar organic selective solvent from substantially co-boiling hydrocarbons. Moreover, the practice of this invention is particularly useful in a solvent refining operation wherein a relatively high boiling selective solvent, such as furfural, as opposed to normally gaseous sulfur dioxide, is employed to solvent refine a relatively light or low boiling petroleum fraction, such as a petroleum naphtha, a heavy naphtha, kerosene, a light lubricating oil and the like, which has an initial boiling point below about 625° F. The practice of this invention is particularly applicable for the recovery of furfural from

raffinate mixes and extract mixes derived from the furfural solvent refining of petroleum fractions which have an initial boiling point of 500° F. or lower. By conventional methods the recovery of furfural from mixes derived from such charge stocks to yield a furfural-free extract and/or a furfural-free extract has been very difficult or substantially impossible.

Although considerable emphasis in this disclosure has been placed upon the applicability of the subject invention with respect to the use of furfural as the selective solvent and for the recovery of furfural, it is mentioned that, as disclosed herein, this invention is applicable for the recovery of any polar organic selective solvent possessing a relatively high boiling point, especially a boiling point approximating the boiling point of components making up a petroleum fraction undergoing solvent refining. More particularly, the practice of this invention is also suitable for use in a solvent refining operation employing a phenol, nitrobenzene, dimethylformamide, or β,β -dichloroethylether and other relatively high boiling selective solvents.

As will be apparent to those skilled in the art many modifications, substitutions and alterations in the practice of this invention as disclosed hereinabove are possible without departing from the spirit or scope thereof.

We claim:

1. A solvent refining process for the solvent refining of a liquid petroleum fraction having an initial boiling point below 625° F. which comprises contacting said petroleum fraction with liquid furfural to yield a liquid raffinate mix containing furfural dissolved in the raffinate and an extract mix containing extract dissolved in the furfural, contacting said raffinate mix in a liquid-liquid contacting operation with a concentrated aqueous solution of sodium xylenesulfonate to extract furfural from said raffinate mix, contacting said extract mix with the concentrated aqueous solution of sodium xylenesulfonate to extract furfural from said extract mix and subjecting the resulting aqueous hydrotropic solutions containing furfural dissolved therein to fractionation to remove furfural therefrom.

2. A method in accordance with claim 1 wherein the resulting aqueous hydrotropic solutions after removal of furfural therefrom are recycled to contact additional raffinate mix and additional extract mix for the removal of furfural therefrom.

3. A solvent refining process for the solvent refining of a liquid petroleum fraction having an initial boiling point below 625° F. which comprises contacting said petroleum fraction with liquid furfural to yield a liquid raffinate mix containing furfural dissolved in the raffinate and an extract mix containing extract dissolved in the furfural, contacting said raffinate mix in a liquid-liquid contacting operation with a concentrated aqueous solution of sodium xylenesulfonate to extract furfural from said raffinate mix, contacting said extract mix with the concentrated aqueous solution of sodium xylenesulfonate to extract furfural from said extract mix and recovering furfural from the resulting aqueous hydrotropic solutions.

4. A method in accordance with claim 1 wherein said petroleum fraction is a light lubricating oil.

5. A method in accordance with claim 1 wherein said petroleum fraction is a heavy petroleum naphtha.

6. A method in accordance with claim 1 wherein after the removal of furfural from the aqueous hydrotropic solution by fractional distillation the resulting aqueous hydrotropic solution is contacted with fresh feed petroleum fraction to remove residual furfural therefrom.

7. A method in accordance with claim 1 wherein said petroleum fraction is in the kerosene boiling range.

8. A method of solvent refining a liquid petroleum fraction having an initial boiling point less than 625° F. which comprises contacting said petroleum fraction with liquid furfural to yield a raffinate mix comprising raffinate containing furfural dissolved therein and an

11

aromatic extract mix comprising furfural and extract dissolved therein, contacting said raffinate mix in a liquid-liquid contacting operation with an aqueous solution of an alkali metal arylsulfonate, said aqueous solution being immiscible with said raffinate mix and said extract mix, to remove said furfural therefrom and employing the resulting aqueous solution, now containing furfural dissolved therein, to remove additional selective solvent from said extract mix.

9. A method of solvent refining a liquid petroleum fraction having an initial boiling point less than 625° F. which comprises contacting said petroleum fraction with liquid furfural to yield a raffinate mix comprising raffinate containing furfural dissolved therein and an aromatic extract mix comprising furfural and extract dissolved therein, contacting said raffinate mix in a liquid-

liquid contacting operation with an aqueous solution of sodium xenesulfonate, said aqueous solution being immiscible with said raffinate mix and said extract mix, to remove said furfural therefrom and employing the resulting aqueous solution, now containing furfural dissolved therein, to remove additional selective solvent from said extract mix.
